UNITED STATES PATENT OFFICE.

BENJAMIN F. SMITH, OF SOMERVILLE, MASSACHUSETTS.

TRACK-DRILLING DEVICE.

SPECIFICATION forming part of Letters Patent No. 592,890, dated November 2, 1897.

Application filed June 7, 1897. Serial No. 639,678. (No model.)

To all whom it may concern:

Be it known that I, BENJAMIN F. SMITH, a citizen of the United States, and a resident of Somerville, in the county of Middlesex and 5 State of Massachusetts, have invented new and useful Improvements in Track-Drilling Devices, of which the following, taken in connection with the accompanying drawings, is a specification.

10 This invention relates to improvements in track-drilling machines for the purpose of drilling rails, girders, &c., and it is carried out as follows, reference being had to the accompanying drawings, wherein—

15 Figure 1 represents a top plan view of the device shown as connected to a railway-rail for drilling holes through the latter. Fig. 2 represents a cross-section on the line 22, shown in Fig. 1. Fig. 3 represents a similar cross-20 section on the line 33, shown in Fig. 1. Fig. 4 represents a detail bottom plan view of one of the hooked bars adapted to be hooked on the foot of the rail during the drilling operation. Fig. 5 represents a detail bottom plan 25 view of the rest-bar and its back-rest. Fig. 6 represents an enlarged cross-section on the line 66, shown in Figs. 1 and 2; and Fig. 7 represents a similar cross-section on the line 77, shown in Figs. 1 and 2.

30 Similar letters refer to similar parts wherever they occur on the different parts of the drawings.

In Figs. 1, 2, and 3, A represents the rail to be drilled, and B B B represent the sleepers of a railroad-track, as usual.

35 The drill-stock-supporting frame is composed of a pair of hooked bars C C, having hooked ends C' C', adapted to be hooked on the outer side of the flange or base portion of 40 the rail, as shown. Each bar C is to be secured to the inner portion of the flange or base portion of the rail by means of an adjustable clamp D, having a perforation for receiving the screw-threaded clamping-bolt 45 E, provided with a tightening-nut e, as shown. The said bolt is adjustable in a slotted perforation C'' in the bar C and is provided in its lower end with a beveled head e', which is longitudinally adjustable in a dovetailed 50 groove C³ on the under side of the bar C, as shown.

By making the head e' of the bolt E bevel-

eled and fitting in a dovetailed groove, as shown and described, the bolt is prevented from dropping out from the groove C³ in the 55 bar C when the nut e is loosened for the purpose of adjusting the clamp D relative to the rail to be drilled.

The free end of each bar C is transversely corrugated, as shown at C⁴, and adapted to 60 be interlocked with the adjustable rest-bar F, provided on its under side with corresponding longitudinal corrugations f, as shown.

The rest-bar F may be adjustably secured to the hooked bars C by means of clamps G, 65 one end of which is made to rest on top of the rest-bar F, and the other end, which is provided with corrugations g, is adapted to be interlocked with the corrugated surface C⁴ on the upper side of the bars C, as shown. 70

Each clamp G is secured in position to the rest-bar F and bar C by means of a screw-bolt H going through a perforation in the clamp G and through a slotted perforation C⁵, as shown. Said bolt H is provided with a bevelled head h', which is longitudinally adjustable in a dovetailed groove C⁶ on the under side of the bar C, as shown.

h' is an adjustable tightening-nut on the screw-bolt H for the purpose of securing the 80 clamp G to the bar C and rest-bar F, as shown.

By having the head h made beveled and adapted to fit within a correspondingly-shaped dovetailed groove C⁶ on the under side of the bar C said bolt H is prevented from 85 dropping out of the bar C when the nut h' is loosened during the adjustment of the rest-bar and their clamping devices.

I is the back-rest for the drill-stock, which is longitudinally adjustable on the rest-bar 90 F and secured to the latter by means of a set-screw i, as shown.

K is the drill, as usual, inserted in the forward end of the drill-holder or drill-stock L. The drill-stock is of the usual construction, 95 having a ring L' surrounding it and adapted to be oscillated on said drill-stock and provided with a pawl-and-ratchet or friction-roller device, as is common in the art, for the purpose of imparting an intermittent rotary 100 motion to the drill during the rocking motion of the lever L'', that is secured to the ring L'.

L³ is a handle, as usual, secured in an adjustable manner to the lever L''.

M is a wrench adapted to fit around a portion of the polygonal feed-sleeve N, by means of which the operator can adjust said feed-sleeve N or hold it stationary while he turns the drilling stock by means of the lever L'', thus causing the drill to be fed forward from time to time, as may be required, without interrupting the drilling operation.

The pointed end of the feed-sleeve N is adapted to rest against the back-rest I, as shown, said rest being preferably provided with longitudinal grooves i' for receiving such pointed end of the said feed-sleeve, as is common in devices of this kind.

By having the rest-bar F adjustable relative to the hooked bars C C and the back-rest I adjustable on the said rest-bar the hooked bars C C may be secured to the rail without interfering with the sleepers B B, as shown, and by the employment of the clamps D D the hooked bars C C are firmly secured to the rail without the need of any device for supporting the rest-bar F in proper position above the sleepers.

The invention is very simple in construction, it can easily be applied to a rail, girder, &c., to be drilled, and when not in use it can be taken apart and stored or transported in a very small compass.

Having thus fully described the nature, construction, and operation of my invention, I wish to secure by Letters Patent and claim—

1. In a track-drilling device in combination, a pair of hooked bars adapted to be secured to the rail and having slots C'', adjustable 35 clamps D, clamping-bolts E each of which being provided with a nut e and having a beveled head e' adjustable in a dovetailed groove C³, on the under side of the respective bars C, C, substantially as and for the purpose set 40 forth.

2. In a track-drilling device in combination, a pair of hooked bars adapted to be secured to the rail, an adjustable rest-bar grooved on its under side and adapted to intermesh with 45 a correspondingly-corrugated surface on the hooked bars, an adjustable clamping device corrugated on its under side adapted to interlock with the corrugated portion of the hooked bar and a clamping-bolt and nut, said 50 bolt having a beveled head fitting in a correspondingly-shaped groove on the under side of the hooked bar substantially as and for the purpose set forth.

In testimony whereof I have signed my 55 name to this specification, in the presence of two subscribing witnesses, on this 27th day of May, A. D. 1897.

BENJAMIN F. SMITH.

Witnesses:

ALBAN ANDRÉN,
CHARLES A. HARRIS.
